UNITED STATES PATENT OFFICE.

JOSEPH OSWALD, OF SAN FRANCISCO, CALIFORNIA, ASSIGNOR TO HARRIS,
OSWALD & NOBLE, OF SAME PLACE.

SPRINKLER.

SPECIFICATION forming part of Letters Patent No. 425,340, dated April 8, 1890.

Application filed February 5, 1890. Serial No. 389,309. (No model.)

To all whom it may concern:

Be it known that I, JOSEPH OSWALD, a citizen of the United States, residing in the city and county of San Francisco, State of California, have invented an Improvement in 5 Lawn-Sprinklers; and I hereby declare the following to be a full, clear, and exact description of the same.

My invention relates to certain improvements in lawn-sprinklers; and it consists, essentially, of a hollow standard, through which water is conveyed, a slightly tapering or inverted conical head fitted to the upper end of said standard, the upper and larger end terminating in a shoulder, against which a correspondingly-shaped sleeve abuts, said sleeve carrying the arms by which centrifugal rotation is produced, and being held in place by a nut which screws upon the lower part of 15 the head, and by which adjustment may be made.

Referring to the accompanying drawings for a more complete explanation of my invention, Figure 1 is an exterior view of my sprinkler. Fig. 2 is a view showing the standard, the inverted tapering head, and a sectional view of the rotary sleeve.

In the manufacture of lawn-sprinklers of that class having a vertical standard and a rotary 30 head with arms, upon one side of which jet-holes are made for the escape of the water, so as to give the sleeve a centrifugal rotary motion, various methods have been employed to provide an easily-running head, and at the same 35 time to prevent or compensate for wear which may take place.

In my invention, A is the vertical hollow pipe or standard, supported by a tripod or legs B at the bottom, and having a coupling 40 C, by which a flexible supply-hose may be united with the bottom of the hollow standard or pipe, so as to convey water into it. At the upper end this standard is screw-threaded, as shown at D.

E is a separate and independent head, which 45 is preferably made of brass or any similar suitable material. This head is made slightly tapering, the smallest end being downward and the largest at the top, and F is an enlarged shoulder or flange cast or fixed upon 50 this head, and serving as a stop for the sleeve which fits upon it. This head is hollow or

tubular in line with the standard A, and its lower end is screw-threaded on the inside, so as to be easily screwed upon the threads a of 55 the standard. By this construction I am enabled to remove the head for repairs, or to replace, if worn out, without disturbing the other parts.

G is a hollow sleeve, the interior of which 6c is accurately bored to fit the exterior of the head, and this sleeve has sockets H formed in its sides about midway of its length, these sockets extending outwardly at right angles with the vertical axis of the sleeve. There may 65 be two, three, or more of these sockets, and they are screw-threaded, so that the arms I fit into them. These arms have small perforations or jet-holes J in their sides and ends, made in the usual manner for this class of 70 rotary sprinklers, so that when water is admitted into the standard and through the holes K in the head it will pass out through these arms, and, acting centrifugally, will cause the sleeve and arms to rotate in the well-known manner for this class of 75 sprinklers.

The head has holes K made transversely through it to allow the water to pass out into the arms of the rotary sleeve, and in order to facilitate the passage of the water I prefer to 80 form a groove or channel around the head at this point. The holes in the head are approximately in line with those in the sleeve and the arms. The upper end of this sleeve abuts against the fixed flange or top F of the 85 head E, and it is held in place by means of a nut M, which screws up from below upon screw-threads N, formed upon the exterior of the lower end of the head E. Between the upper end of the sleeve and the flange F, at 90 the top of the head, I prefer to fit a removable washer O, this washer serving to prevent wear upon the flange, and it may easily be replaced at any time when worn out. It will also be manifest that by placing a washer of 95 some thickness at this point the sleeve may be fitted to as close a joint as may be needed upon the head, and if any wear takes place which would tend to cause leakage by reason of too much space between the sleeve and the head a thinner washer can be substituted, which will allow the sleeve to slip farther up on the head, and thus maintain a close fit.

By means of the nut M, which screws upon

the bottom of the head, the sleeve may be raised or depressed, so as to change its fit upon the head. When water is admitted under pressure into the standard, it passes out into the centrifugally-acting arms of the head, and the tendency of the water-pressure being to lift the sleeve it will be forced up against the washer at the top, and will thus always keep a close joint at this point.

I am aware that vertical standards having centrifugally-rotating heads and perforated arms have been employed as sprinklers, and I am also aware that such heads have been fitted upon the upper end of the standard, so as to slip on from above. I do not claim these devices, broadly; but

What I do claim as new, and desire to secure by Letters Patent, is—

1. In a lawn-sprinkler, the hollow tubular standard having its upper end screw-threaded, the independent head in the form of an inverted frustum of a cone removably fixed upon the standard and having a flange or cap integral with and projecting around its upper and larger end, in combination with a sleeve having the perforated radial arms projecting

from its sides, the interior of said sleeve being fitted to the inverted conical head, about which it turns, and a nut screwing upon the bottom of the head, whereby the sleeve is supported and adjusted from below, substantially as herein described.

2. In a lawn-sprinkler, the vertical hollow conducting-standard, the independent separable head in the form of an inverted frustum of a cone, having a permanent flange or cap at its upper end and water-escape openings through its sides, as shown, in combination with the sleeve having the radial perforated arms and the interior fitted upon the lower end of the head, a nut screwing upon the lower end of the head and supporting and adjusting the sleeve from below, and a removable washer fitted between the upper end of the sleeve and the projecting flange of the head, substantially as herein described.

In witness whereof I have hereunto set my hand.

JOSÉPH OSWALD.
